RADIATOR BYPASS DEVICE

Fred M. Young, Racine, Wis.

Application September 12, 1936, Serial No. 100,466

3 Claims. (Cl. 257—125)

The present invention pertains to a by-pass device for radiators, having preferably thermal controlling means whereby the cooling liquid is directed through the radiator tubes only after the desired temperature is reached and whereby the cooling liquid is directed through a few large tubes only when its temperature is below this desired point, these large tubes being preferably positioned out of the path of the cooling air.

The object of this invention is to provide separate chambers at the ends of one of the headers and operatively connect these chambers to the other header by means of a few large by-pass tubes, each having an expansion joint to thereby provide for unequal expansion and contraction between the core and these tubes.

A further object is to provide a novel by-pass connection to the tube plate, thus to prevent leakage or loosening of the joint.

To these and other useful ends this invention consists of parts and combinations thereof or their equivalents as described and claimed and shown in the accompanying drawings in which:

Fig. 1 is a front elevation of a radiator equipped with the preferred form of my invention.

Fig. 2 is a side elevation of the device as shown in Figure 1, a portion of the large tubes and the air shield being removed.

Fig. 3 is an enlarged partially sectioned view illustrating the expansion joint shown in Figures 1 and 2.

Fig. 4 is an enlarged partially sectioned view of a modified form of the expansion joint.

Fig. 5 is an enlarged fractional top view of the tube plate illustrating the tube ends in position.

Fig. 6 is an enlarged fraction of the radiator taken on line 6—6 of Figure 5.

Fig. 7 is an enlarged fractional section of the header taken on line 7—7 of Figure 1, the portions cut away in a manner to thereby show a fraction of the tube plate and fins.

Fig. 8 illustrates in horizontal section, one form of a device adapted to automatically shift the cooling liquid from the large tubes to the finned tubes and back again.

As thus illustrated numeral 10 designates the tubes of the core which, as illustrated, are preferably flattened in cross section. Numeral 11 designates the fins of the core which are provided with flanged openings through which the tubes extend as is customary in radiators of the class. I provide tube plates 13 each having flanged openings 14 for the reception of the ends of tubes 10. As is the custom, the tubes are suitably bonded

to the fin flanges and to the tube plate flanges, thus forming a conventional core.

I provide a suitable number of by-pass tubes 16. These tubes are positioned in transverse rows at the sides of the core and spaced a suitable distance from the core to thereby provide room for the air directing partitions 17. These members 17 are suitably secured to the tube plate or otherwise held into position. Thus means are provided whereby the cooling air may be prevented from contacting tubes 16, the object being to reduce the time required to heat the engine to the most economical operating temperature. It will be understood that the fan shroud at its forward vertical edges contacts members 17 thus all of the air moved by the fan will be confined to the space between these members.

Clearly there will at times, be a considerable difference in temperature between the tubes 10 and 16; and further, when the ends of the headers are secured together by means of housing members, unequal expansion between tubes 16 and the housing members will be considerable. Therefore, I provide expansion joints in tubes 16 preferably near the ends thereof as illustrated. These joints, as illustrated in Figures 1, 2 and 3, are formed of suitable material and comprise end sleeves 20 and folds 21, forming a bellows which is flexible enough to permit free expansion and contraction in tubes 16.

In Figure 4 I illustrate a modified form of expansion joint wherein a rubber hose 22 is placed on the tube ends as shown and secured thereto by means of hose clamps 23. Clearly the device illustrated in either Figure 3 or 4 will yield sufficiently to prevent excessive strains caused by unequal expansion and contraction.

One of the novel features of the present invention is the manner of securing the by-pass tube ends to the tube plates. I provide a sleeve 25 which is first secured to tube 16 and the tube end then inserted into flanged opening 15, the sleeve ends contacting member 13 as illustrated, with the tube ends protruding. The protruding ends 45 are then folded over the end of flange 15 as at 26, the tube ends being of a length as will contact the tube plate as at 27, the sleeve 25 answering to prevent flanges 15 from being moved by the pressure required to fold the tube ends around the 50 flanges. After this folding operation the joint is bonded either by dipping or by applying heat, acid and bonding material in the usual way. In either method of bonding, the bonding material will flow by capillary attraction, fill in between 55

the metals and form fillets at the corners as indicated in Figure 6.

After completion of the core assembly as illustrated and described, the header caps 30 and 31 are secured to the tube plates as follows: header cap 31 is conventional in shape; header cap 30 is provided with partition walls 32 forming L shaped chambers 33, in the bottom of which are provided openings 34 which register with the ends 10 of tubes 16. A gasket 35 is positioned between the headers and partitions 32 and the tube plates whereby the tube ends 16 are operatively connected to chambers 33 and the tubes 10 are operatively connected to the headers. Flanged 15 openings 36 register with chambers 33 and flanged openings 37 register with the header chamber. The header caps are secured to the tube plates as indicated, by means of suitable steel bars 38 and bolts 39; thus the assembly is securely bound 20 together and compartments 33 are isolated from the header chambers.

It is customary to provide housing members between the header ends. These members have for convenience been omitted. Clearly when 25 rigid housings are supplied there is an added reason for applicant's expansion joints.

Headers 30 and 31 are operatively connected to the engine jacket preferably by means of rubber hose connections in the usual manner. I provide a thermally controlled valve whereby openings 36 are caused to receive the cooling liquid when its temperature is below a predetermined point, and when the temperature rises to the desired point, which is the point at which the 35 engine will operate most economically, openings 36 are shut off and openings 37 are permitted to receive the cooling liquid. A unitary thermally controlled valve may be secured to these openings; thus a single hose connection may lead from 40 each valve to the engine.

When the engine is started the temperature will rise quickly since the cooling liquid first passes through tubes 16, and when it reaches the predetermined point, the thermostat regulator will 45 cause the cooling liquid to pass through tubes 10.

In Figure 8 I illustrate a valve mechanism having a thermally sensitive device which is adapted to direct the cooling liquid through tubes 16 until it reaches a desired temperature after 50 which this mechanism is adapted to direct the cooling liquid through the finned tubes.

I provide a bracket 40 which is suitably secured over inlets 36 and 37 as illustrated and having an inlet opening 41 which is suitably connected 55 to the cooling jacket of the engine. This bracket is provided with outlet ports which register with

ports 36 and 37 and a valve 42 suitably journaled on a shaft 43 and being adapted as is clearly illustrated, to either direct the liquid from inlet 41 to port 36 or from this inlet to port 37 as follows:

I provide preferably a thermally sensitive Sylphon 44 which is pivotally anchored to an arm 45 and having at the other end an arm 46 which is pivotally secured to valve 42 in the position shown. Thus when the passing liquid is below 10 the desired temperature, Sylphon 44 will be contracted and the valve 42 will be positioned about as shown, and after the temperature of the cooling liquid rises to say 175°, the Sylphon will be expanded enough to move this valve so as to direct the liquid into port 37; thus the action of this device will be automatic. I may however, elect to make use of a manually controlled valve.

Thus it will be seen that the cooling liquid will be thermally controlled; that the by-pass tubes 20 may expand and contract independent of the core tubes and that they are secured to the tube plates in a manner which will insure against fractures and leakages.

Having thus shown and described my invention, 25 I claim:

1. A radiator of the class described, comprising headers and finned tubes operatively connected therebetween, one of said headers having a partition forming a separate end compartment, a 30 number of relatively large tubes operatively connecting said compartment to the adjacent end of the other header, openings on opposite sides of said partition and having means whereby the cooling liquid may be directed either through 35 said large tubes or through said finned tubes, expansion joints in said large tubes to thereby permit unequal expansion between said large and finned tubes.

2. A radiator of the class described, comprising 40 headers and finned tubes operatively connected therebetween, one of said headers having partitions forming separate compartments at each end, a number of relatively large tubes operatively connecting said compartments to the adjacent 45 ends of the other header, openings on opposite sides of said partitions and having means whereby the cooling liquid may be directed either through said large tubes or through said finned tubes.

3. A radiator as described in claim 2 including, 50 expansion joints in said large tubes to thereby permit unequal expansion between said large and finned tubes.
